UNITED STATES PATENT OFFICE

GOTHARD LOWENSTEIN, OF BROOKLYN, NEW YORK

TRAVELING TURNTABLE EQUIPMENT FOR GARAGES

Application filed December 7, 1927. Serial No. 238,406.

This invention relates to improvements in garages and garage equipment and more particularly refers to an improved arrangement of carrier to be used for speeding up internal traffic in garages, and guiding means therefor.

The primary object of this invention is to provide a traveling platform of a novel and improved design adapted to transport and change the direction of vehicles being moved from one point of the garage floor to another.

Another object is to provide in combination with a platform adapted to transport and to change the direction of vehicles supported thereby, a novel arrangement of guiding means therefor, making it easy to propel and to turn said platform in various predetermined directions, according to the position occupied by said platform on a garage floor.

A further object is to provide a novel and improved arrangement of garage floor, calculated to increase the efficiency of traffic on said floor and permitting the efficient use of available storage space.

Other objects and advantages of the present invention will more fully appear as the description proceeds and will be set forth and claimed in the appended claims.

The efficient operation of a garage is largely dependent upon the manner in which the available storage space is made use of and upon the speed with which the necessary movements for vehicles to move to and from their places of storage and the entrance to or the exit from the floor can be effected.

As a general rule, these two requirements are antagonistic to each other, since the more space is devoted to the storage of vehicles and the less space is left for the vehicles to move about the garage floor, so that in the average garage, a material proportion of the floor space is left empty, and yet, the movement of vehicles can only be effected with considerable delay.

Various arrangements have therefore been resorted to in order to conciliate these two conditions in a manner permitting of using

to the best efficiency, the storage space available, at the same time insuring speedy handling of vehicles to and from their storage stalls.

Such arrangements are incidentally advantageous in cutting down to a minimum the number of mishaps and slight accidents which are now a matter of common occurrence in garages, and which go to increase the cost of operating a garage to a very material extent.

Many such arrangements which have come to my notice however, require specially built buildings or costly alterations to existing buildings so that they are ill adapted for general use. One of the aims of my present invention is to provide a simple and relatively inexpensive arrangement for bettering traffic conditions on a garage floor, and for otherwise improving the operating efficiency of a garage. By way of example, an embodiment of my invention is illustrated in the accompanying drawings, in which:

Fig. 1 is a plan sectional view of a typical garage floor, equiped with vehicle handling means, coming within the scope of my invention; and

Fig. 2 is a side view in elevation of a carrier also embodying my invention, adapted for use on a garage floor.

My invention essentially consists in transporting vehicles from one point of a garage floor to another by means of a platform on which said vehicles are supported, said platform being adapted to travel from one point to another and being also adapted to rotate on a horizontal plane; so that the carrier can both transport and change the direction of the vehicles supported thereby.

In its preferred embodiment, the invention also comprises means for guiding the carrier during the course of its movements, said means constituting also positioning means insuring the proper alignment of the vehicles carried by said carrier.

My invention will be better understood by referring to said drawings, in which, 10 designates a garage floor provided with a front entrance 11, the width of said floor being sufficient to accommodate two longitudinal

rows of vehicles 12, 13, 14, 15, and two longitudinal runways 16, 17, serving rows of vehicles 12—13, 14—15, respectively.

It will be observed that while vehicles entering or leaving the floor through entrance 11 have their axis longitudinally directed, the vehicles stored in their respective stalls are transversely directed with respect to said entrance; accordingly, I provide means for turning the vehicles 90° to the right or to the left, when they reach one of the runways, so as to avoid the necessity of difficult maneuvering for driving vehicles to their respective stalls.

To this end, I provide a platform 18, with four casters such as 19 enabling it to travel in any direction and also enabling it to turn in a horizontal plane about its own axis.

I provide said platform with some suitable operating means such as, for instance, hand levers 20, 21, and I am therefore enabled to move the platform to any desired point on the floor.

In order to make it easier for vehicles to be driven on or off the platform, I provide a runway for said platform sufficiently depressed to permit the platform to come very close to the floors.

In the arrangement illustrated in the drawing, it is sufficient to provide a runway extending longitudinally between rows of vehicles 12, 13, as shown at 16; another runway extending longitudinally between rows of vehicles 14, 15 as shown at 17 and another transversal runway 22 in front connecting said lateral runways.

In this manner, the carrier may be brought directly opposite entrance 11 as shown and can be moved in one or the other direction along transversal runway 22 until it reaches one of the two lateral runways, when it can be turned around 90° thus setting the vehicle carried thereby transversely to the direction of the entrance.

The carrier can then be caused to travel along the longitudinal runway thus reached, until it may be stopped directly opposite the stall that the vehicle or the carrier is to occupy. At this point, the vehicle being already set in the proper direction, can be driven on its own power off the platform and onto its storage place.

The reverse takes place when a vehicle is to be moved from its storage place to the entrance, or exit.

The depressed runway may be of a width corresponding to the distance between the outer surfaces of the casters with which the platform is provided; but in order to leave the level of the floor as uniform as possible, I prefer to provide comparatively narrow individual runways for the two sets of wheels, one at each side of the platform, said individual runway being indicated at 16', 16", 17', 17" and 22', 22".

These runways being relatively narrow, they do not prevent the free travel of vehicles across the floor in case the same should be needed, so that the floor can be used in the ordinary manner.

By virtue of this arrangement, it is also possible when all the stalls in longitudinal rows for vehicles 12, 13, 14, 15 are occupied, to use also the longitudinal runways as temporary additional storage space, if desired.

Accordingly, transversal runways 22', 22" intersect longitudinal runways 16'—16", 17'—17", and at the points of intersection circular runways 23, 24 are provided, adapted to receive all the four wheels of the platform, when the same is caused to rotate about its own vertical axis.

In order to facilitate the maneuvering of the platform, the same is moved along transversal runways 22'—22", in one or the other direction, until the edge of the platform strikes a roller 25, 26, arranged to rotate in a horizontal plane.

These rollers thus act as positioning means for the platform defining the positions at which the platform is to be turned 90° in one or the other direction, before being driven through runways 16'—16" or 17'—17".

From the foregoing description, it will be seen that all the movements of vehicles to and from their places of storage can be speedily and safely effected by employing means of an excessively simple and inexpensive nature.

It will be observed that in the preferred embodiment described, the casters are imprisoned between the side surfaces of the runways within which they travel, so that they serve to prevent displacements of the platform transverse to the direction of the runway, such as might be caused by the impact of a vehicle being driven on or off the platform.

It will be observed that while the drawings show a traveling turn table equipped with casters underneath the platform, it is also possible to conceive a construction of turn table where the underside of the platform is but slightly higher than the underside of the wheels of the supporting casters.

The advantage of such a construction is that the platform will be practically on a level with the floor without the necessity of providing recessed trackways therefor. Such a construction may be obtained by resorting to an arrangement similar to that described in connection with a carrier forming the object of another application entitled, Traveling turn table, Ser. No. 227,756, co-pending herewith.

The specific feature of said carrier is that the shafts on which the wheels are mounted are supported above the platform, the wheels

projecting through openings provided in the platform in correspondence thereof.

A parallel construction may be adopted in the present case, by mounting the caster pivots on frames upwardly projecting from the platform, and in providing openings through said platform wide enough to permit free steering of the caster wheels.

It is obvious that the other various details of construction may vary in practice from those shown and described without substantially departing from the inventive idea; therefore, I reserve myself the right to carry my invention into practice in all those ways and manners which may enter fairly, into the scope of the appended claims.

I claim:

1. In a building for the purpose described, the combination with a storage floor, of a carrier comprising a vehicle supporting platform and supporting casters therefor, said supporting casters being adapted to carry said platform along a linear path and being also adapted to follow angular movements of said platform about its vertical axis, and sunken individual tracks in said floor for the supporting casters at each side of said platform, guiding said carrier along a predetermined path of travel, the depth of said tracks substantially corresponding to the vertical distance between the lower surfaces of said casters and the edge of said platform.

2. In a building for the purpose described, the combination with a storage floor, of a carrier comprising a vehicle supporting platform and supporting casters therefor, said supporting means being adapted to carry said platform along a linear path and being also adapted to follow angular movements of said platform about its vertical axis, a sunken trackway comprising a plurality of linear tracts running at an angle to each other, each tract comprising an individual track for the supporting casters at each side of said platform, and a circular track on a level with said trackway tracts connecting said linear tracts at their junction points permitting angular displacements of said carrier, the depth of said tracks substantially corresponding to the vertical distance between the lower surface of said casters and the edge of said platform.

3. In a building for the purpose described, the combination with a storage floor, of a carrier comprising a vehicle supporting platform, and four supporting casters therefor, a sunken runway for said carrier comprising a transversal and a longitudinal tract, each tract comprising an individual track for the casters at each side of said platform, said tracks being adapted to guide said carrier along their linear paths preventing angular movements thereof

about its vertical axis, and a circular track at the junction point of said transversal and longitudinal tracts, said circular track being on a level with said trackway tracts and being adapted to receive and to guide said casters while said platform is angularly displaced about its vertical axis, the depth of said tracks substantially corresponding to the vertical distance between the lower surface of said casters and the edge of said platform.

4. In a building for the purpose described, the combination with a storage floor, of a carrier comprising a vehicle supporting platform, and four supporting casters therefor, a sunken runway for said carrier comprising a transversal and a longitudinal tract, each tract comprising an individual track for the casters at each side of said platform, said tracks being adapted to guide said carrier along their linear paths preventing angular movements thereof about its vertical axis, a circular track at the junction point of said transversal and longitudinal tracts, said circular track being on a level with said trackway tracts and being adapted to receive and to guide said casters while said platform is angularly displaced about its vertical axis, and positioning means delimiting the position of said platform when its vertical axis coincides with the center of said circular track.
